UNITED STATES PATENT OFFICE.

JOSEPH H. MURRAY, OF HOMER, GEORGIA.

CHURN.

1,194,768.

Specification of Letters Patent. Patented Aug. 15, 1916.

Application filed November 8, 1912. Serial No. 730,244.

To all whom it may concern:

Be it known that I, JOSEPH H. MURRAY, a citizen of the United States, and a resident of Homer, in the county of Banks and State 5 of Georgia, have invented certain new and useful Improvements in Churns, of which the following is a specification, reference being had to the accompanying drawings.

This invention relates to certain new and 10 useful improvements in churns operated by a spring driven train of gearing.

The primary object of my invention is to provide a churn, the dasher of which is driven by a spring operated train of gearing, and which includes a simply operated 15 deterrent for stopping the gearing and a special means for holding the churn to the operating mechanism and the lid to the churn.

With these and other objects in view, the 20 present invention consists in the combination and arrangement of parts as will be hereinafter more fully described and finally pointed out in the appended claim, it being further understood that changes in the 25 specific structure shown and described may be made within the scope of the claim without departing from the spirit of the invention.

In the accompanying drawings forming a 30 part of this specification and in which like numerals of reference indicate similar parts in the several views: Figure 1, shows a side view partly in section of a churn embodying my invention. Fig. 2, is a front view 35 thereof. Fig. 3, is a section on line 3, 3 of Fig. 1. Fig. 4, shows a fragmentary detail of the detent.

In my present invention I provide a simply constructed mechanism arranged to 40 drive the dasher of a churn, with a holder by holding the churn in working position.

In the accompanying drawings, the numeral 11 designates a suitable base to which is secured the vertical standard 12. Fixed 45 to this standard is the housing 13, this housing being secured to the standard by means of the bolts 14. Held within this housing is the main shaft 15, having a driving gear 16, and a driving spring 17 together with a 50 ratchet 18, as is usual in spring driving trains. Located above the shaft 15, is a shaft 21, provided with the pinion 20 and the gear 22, this gear 22 meshing with the pinion 23 secured to the shaft 24, which also 55 gives support to the gear 25. The gear 25 in turn meshes with the pinion 26, upon the

shaft 27, to which is fixed a gear 28 meshing with the pinion 29 secured to the crank shaft 30, which also carries the gear 31. This gear 31 in turn meshes with the pinion 32 upon the fan shaft 33 which carries the fan 34, operating the governor. Secured to the crank 35, fixed to the shaft 30, is the pitman 36, which at its lower end is pivotally secured to the upper end 37 of the reciprocating rod 38, which slides within the bearings 39, and at its lower end has the collar 40, provided with the set screw 41.

The churn is shown at 45 and is provided with the lid 44, within which is held the 70 dasher staff 42 at its lower end supporting the dasher 46. This staff 42 is held within the collar 40 by means of the set screw 41.

By means of a suitable crank 19, the spring 17 may be wound up so that it will, 75 in unwinding, drive the train of gearing described. In rotating the shaft 30 actuates the crank 35, and the pitman 36, as well as the connecting rod 38 to impart a proper movement to the dasher staff and dasher, to 80 insure the full and proper churning of the cream within the churn.

In order to properly hold the churn in place, I provide the standard 12, with a bracket 53, which is secured by means of the 85 bolts 54. This bracket has an off set and upstanding end 52, with a slot 55, within which is adjustably held the bolt 58. This bolt carries the clamping collar 57, having the two bowed clamping arms 57' as clearly 90 shown in Fig. 3. These bowed clamping arms 57' are arranged to clasp the neck or upper end of the churn 45, in the manner shown in Figs. 1 and 3. In order to securely hold the churn to the clamp, I provide the clamp bolt 59, with the wing nut 60, arranged so that in screwing up the wing nut 60, the arms 57' are securely clamped upon the churn.

As shown in Fig. 2 each clamping arm 57' 100 is provided with a spring hook 61, these hooks being arranged to press upon the lid 44 of the churn, to hold the lid in secured condition, while the churn is in working position as shown in Fig. 2.

A fly brush can be easily attached to the dasher or reciprocating rod 38. The spring driving the train of gearing is of such a strength that one winding of the spring will suffice to fully complete one churning operation.

In order to stop the train of gearing at

any desired instant, I provide the shaft 21, with a ratchet wheel 47, shown in Fig. 4 and held adjacent to this ratchet wheel 47 is the pawl 48, operated by means of the handle 50. Positioned above the pawl is a stop lug 51. During the time the gearing is in operation, the pawl 48 rests against the lug 51, as shown in dotted lines in Fig. 4, where the pawl is shown as locking the ratchet 10 wheel 47.

The device is of a simple and inexpensive nature, and both durable and efficient in operation and the churn can be secured to or detached from the holding mechanism with 15 ease, accuracy and despatch.

Having thus described my invention what I claim as new and desire to secure by United States Letters Patent is:—

The combination with a churn and its lid, 20 of a base, a standard secured to said base, a

bracket secured to said standard having an upstanding offset end provided with a slot, a bolt adjustably held within said slot, a clamping collar held upon said bolt having two bowed clamping arms arranged to 25 clamp the neck of said churn, a clamping bolt passing through said arms, a wing nut upon said bolt to clamp said arms upon said churn and hold said churn to said base, and an upstanding spring hook secured to each 30 arm the upper ends of said hooks being arranged to press upon said lid, whereby said lid is held in secured position.

In testimony whereof I affix my signature, in presence of two witnesses.

JOSEPH H. MURRAY.
